UNITED STATES PATENT OFFICE.

CHARLES WOLF, OF BROOKLYN, NEW YORK.

HANDLE CONNECTION FOR HAND BAGS AND THE LIKE.

Application filed June 16, 1927. Serial No. 199,342.

This invention relates to hand bags and has particular reference to an improved handle connection especially designed for women's hand bags, pocketbooks and the like.

The invention comprehends an improved handle connection for hand bags or the like, which in addition to being neat and attractive in appearance is strong and durable, simple in construction, economical to produce and 10 which is highly efficient in its purpose.

The invention furthermore comprehends a method of establishing connection between a hand bag and a handle therefor, which greatly facilitates the operation of establishing 15 such a connection while reducing the expense ordinarily entailed in this operation.

With the above recited and other objects in view, reference is had to the following specification and accompanying drawings in which 20 there is exhibited one embodiment or example of the invention, the actual scope of which is defined by the appended claims.

In the drawings

Figure 1 is a perspective view of a hand 25 bag having a handle connection constructed in accordance with the invention;

Figure 2 is an enlarged detail sectional view taken approximately on the line indicated at 2-2, Figure 1;

30 Figure 3 is a similar sectional view taken approximately on the line indicated at 3-3, Figure 1;

Figure 4 is a perspective view of the back- 35 ing plate removed.

35 Referring to the drawings by characters of reference, 10 designates a hand bag or pocketbook body, 11 the handle, and 12 the connecting link which may assume various forms and shapes but which essentially has inward- 40 ly directed alined terminals 13 constituting trunnions, the remainder of the connecting link extending through a looped terminal 14 of the handle 11.

The invention resides in the mode or means 45 of connection between the link 12 and the hand bag body, which connection consists of a backing plate 15 which is preferably of thin sheet metal and which is arranged on the inner surface of the hand bag body material 10.

50 The plate is preferably covered with a staying cloth 16, and the hand bag backing plate and staying cloth are slitted to provide a parallel pair of spaced slits, after which the material or portions between the slits are bent 55 outwardly into substantially semicylindrical form, as indicated at 17. Likewise the por-

tions of the bag body, plate and staying cloth beyond the outwardly bent bearing portion are depressed inwardly at 18.

The trunnions or terminals 13 of the connecting link 12 are engaged in the opposite ends of the bearing 17. This arrangement establishes a firm, lasting, and inexpensive connection which in no way detracts from the general appearance of the hand bag or pocket- 60 book. 65

In the drawing, 19 designates the usual card board or other stiffening elements, and 20 the inside lining which conceals the slitted portions from view when the pocketbook is open. 70

The method of producing a hand bag handle bearing for the reception of a connecting link consists essentially in securing a metallic plate on the inner side of the hand bag body, forming spaced, parallel slits through the 75 body and plate and then presing the portions of the body and plate lying between the slits outwardly into semicylindrical form for the reception of the connecting link.

In practice it is proposed to adhesively secure the staying cloth to the inner surface of the backing plate and the body material of the hand bag, it being understood that the staying cloth will be of a larger area than the plate so that the plate area will be entirely within 85 the confines of the staying cloth therein.

I claim:

1. A handle connection for hand bags and the like, comprising a metallic backing plate within the hand bag body, and registering 90 parallel slitted portions in the bag body and plate bent outwardly to provide a bearing for the reception of a handle attaching means.

2. A handle connection for hand bags and the like, comprising a metallic backing plate within the hand bag body, and registering 95 parallel slitted portions in the bag body and plate bent outwardly to provide a bearing for the reception of a handle attaching means, the portions of the bag body and plate beyond the outwardly bent bearing being inwardly disposed to facilitate the insertion of the ends of the handle attaching link into the bearing.

3. A handle connection for hand bags and the like, comprising a metal backing plate within the bag body, a staying cloth over the plate, and registering parallel slitted portions in the bag body, staying cloth and plate bent outwardly to provide a bearing for the reception of a handle attaching link. 100 105

4. A handle connection for hand bags and the like, comprising a metal backing plate 110

within the bag body, a staying cloth over the plate adhesively attached to the inner surface of the bag body and plate, and registering parallel slitted portions in the bag body, the staying cloth and plate bent outwardly to provide a bearing for the reception of a handle attaching link.

5. A method of producing a hand bag handle bearing for the reception of a connecting link, consisting in securing a metallic plate upon the inner side of the hand bag body, forming two spaced parallel slits through the

body and plate and pressing the portions of the body and plate lying between the slits outwardly into a semi-cylindrical form for the 15 reception of the connecting link.

6. A hand bag handle bearing for the reception of a connecting link, comprising a metallic backing plate disposed inside of the body material of the hand bag, and an out- 20 pressed slitted portion of said body material and backing plate.

CHARLES WOLF.
